United States Patent Office

Des. 203,922
Patented Feb. 22, 1966

203,922

HARD SURFACE FLOOR COVERING OR SIMILAR ARTICLE

Hubert J. FitzGerald, East Hempfield Township, Lancaster County, Pa., assignor to Armstrong Cork Company, Lancaster, Pa., a corporation of Pennsylvania

Filed Aug. 31, 1964, Ser. No. 81,505

Term of patent 14 years

(Cl. D92—17)

Fig. 1

Fig. 2

FIGURE 1 is a plan view of a hard surface floor covering embodying my new design, with a design unit being enclosed within the outermost horizontal and vertical lines which unit is repeated in regular succession as indicated by the extensions beyond the unit boundaries, and

I claim:

The ornamental design for a hard surface floor covering or similar article, substantially as shown and described.
